UNITED STATES PATENT OFFICE.

LEWIS SCRIVEN, OF BROOKLYN, NEW YORK.

ANNUNCIATOR.

Application filed February 21, 1924. Serial No. 694,344.

This invention relates to annunciators and similar apparatus and more particularly to electrical operating means for such apparatus.

5 In the usual commercial types of annunciators, an announcing target is so arranged and controlled that it is locked in announcing and in silent position by means of an electrically controlled lock or catch and is prevented from moving out of such position until the lock or catch is released. When the catch is released, the target is moved into announcing position by electric means associated with the catch device. 10 15 This arrangement not only renders the mechanism complex, and correspondingly expensive, but the mechanism also tends to chatter when used with alternating current, owing to the vibration of the lock or catch device and the other mechanism as the magnetic field changes with the alternations of current.

These disadvantages and defects are obviated by my present invention, an object 25 of which is to provide a mechanism which will operate equally well and noiselessly with either alternating or direct current.

Another object of the invention is to provide a simple and inexpensive annunciator 30 operating mechanism in which the annunciator target is moved to, and retained in, its positions without the use of a locking means.

Further objects of the invention are, to provide an electric operating means for annunciators which may be very efficiently operated with a minimum of current, and to provide a mechanism in which the magnetic flux produced by an energizing current may be brought to act on a tilting or moving 40 armature without loss or diminution and without causing end thrusts on the armature bearings.

With these and other objects in view, the invention comprises the mechanism described and set forth in the following specification and claims.

The various features of the invention are illustrated in the accompanying drawings in which:

50 Fig. 1 is a perspective view of an annunciator drop embodying a form of my invention, the target of the mechanism being shown in announcing position in full lines and in withdrawn or silent position in broken lines,

Fig. 2 is a sectional view of the annunciator taken on line 2—2 of Fig. 3,

Fig. 3 is a plan view of the annunciator drop,

Fig. 4 is a sectional view of the annunciator taken on line 4—4 of Fig. 2, and,

Fig. 5 is a diagram of a wiring arrangement illustrating an installation of the annunciator.

In my present invention, the core of an electromagnet for actuating an annunciator drop or target is mounted in an iron frame which serves to conduct the entire magnetic flux of the electromagnet from one end of the core of the magnet to within a short distance of the other end, forming in the short space between the frame and the end of the core, an air gap and magnetic field through which substantially the entire magnetic flux of the electromagnet passes. A tilting armature, carrying an annunciator target, is so pivoted on the frame that it is attracted and drawn into the air gap by the attraction of the magnetic field and is thereby tilted to bring the target into view or into announcing position. The armature is so proportioned and mounted that it is overbalanced on its pivot and when its center of gravity passes over the center line of its pivot, it tends to reach and remain in extreme announcing position until positively tilted to the opposite side of its pivot, by a resetting means, which may be a mechanical device or an electromagnet similar to the actuating magnet but acting on the opposite end of the armature. When reset, the armature remains in position until positively actuated by the electromagnet. Besides acting as a flux conductor, and support for the electromagnet cores and armature, the frame may also support a stop for the armature, a card holder and other devices.

Referring more particularly to the accompanying drawings, an actuating electromagnet 10 is provided with a core 12, which is mounted at one end on, and in direct or close contact with, the rear end 14 of a supporting frame 16, of magnetic material such as iron. The frame 16 extends, at 18, at one side of the electromagnet 10, to a front wall or member 20 extending in front of, and spaced slightly from, the front end of the core 12 to form a short air gap 22 therewith. The frame thus serves to conduct the magnetic flux from the rear end

of the core 12 to within a short distance of its front end, from which it passes with undiminished intensity across the air gap, creating therein a magnetic field of the maximum strength from a given amount of electric energy.

When the electromagnet 10 is energized and a magnetic field formed in the air gap 22, it tends to draw downwardly into this field an arm 24 of an armature 26 mounted on a rock shaft or pintle 28 extending between the front and rear ends 14 and 20 of the frame 16. To facilitate the action of the magnetic field, the end of the armature arm 24 is provided with a depending tail 30 which extends into, or to the edge of, the magnetic field of the air gap 22 and increases in width up to the main portion of the arm 24, which is widened, as at 32, to correspond with the area of the air gap.

When the armature has reached its proper position in the air gap 22, further movement is prevented by a stop 34, mounted on the front end of the frame below the armature, on which the lower edge of the armature and the inner edge of the tail 30 rest when the armature reaches its proper announcing position.

To reduce the resistance in the magnetic circuit to a minimum, the width of the air gap 22 is made just sufficient to permit the insertion with sufficient clearance, of the armature arm 24 and tail 30. As all of the magnetic flux of the electromagnet is conducted through the frame without diminution or division, the magnetic attraction between the front face of the armature and the front end of the frame is equal to that between the rear face of the armature and the front end of the core. These forces, therefore, which act longitudinally or axially on the armature, are balanced and all end thrusts on the armature bearings are eliminated. Through this arrangement the frictional resistance to the tilting of the armature is greatly lessened, which, together with the strengthening of the tilting force renders the action of the electromagnets very efficient.

An upright arm or standard 36 is mounted centrally, and preferably integrally, on the armature 26 and carries at its upper end a target 38 so positioned as to come into view as the armature is tilted into the announcing position as indicated in Fig. 2. The upright 36 is preferably offset forwardly to bring the target more prominently into view. The armature 26, upright 36, and target 38 are so proportioned that they are in a state of unstable equilibrium relative to the pivotal support on the shaft 28 and, accordingly, as the arm 36 moves to one side or the other of the vertical line 4-4 through the axis of the pivot, the target tends to fall further from the center line

until the lower edge of the armature comes to rest on the stop 34. Accordingly, after the magnet 10 has been de-energized, the target will remain in its announcing position until it has been positively moved to reset position, without the necessity of locking it in position.

The armature and target may be reset by any suitable mechanical means or by a second electromagnet 40 positioned on the opposite side of the shaft 28 in a manner similar to that of the electromagnet 10, the frame, in this case, having a suitable side extension 42 and rear face 44, the electromagnet and core being so proportioned as to form a suitable air gap 46 into which the opposite arm 48 of the armature 26 may tilt when the electromagnet 40 is energized. The arm 48 is provided with a tail 50 and an enlarged portion 52 similar to the tail 30 and enlarged portion 32 of the arm 24, and is otherwise symmetrical with the arm 24 so that, as the target 38 swings past the center line 4-4, it will continue to move until the lower edge of the arm 48 reaches the stop 34.

The frame 16 is mounted at its rear end on a supporting plate 54 by means of screws 56, which also serve to secure the cores of the electromagnets 10 and 40 in the frame. The rock shaft 28 is supported in a bearing opening 58 in the front wall 20 of the frame, in which a stepped neck portion 60 of the shaft projects, and an aligned opening 62 in the plate 54, a brass plate 64 being inserted between the coned end of the shaft and the opening 62 and dented into the opening 62 to form a suitable bearing.

Current is conducted to and from the electromagnet 10 through suitable contact jacks 66 mounted on a depending portion, of insulating material, of the rear washer 68 of the electromagnet, and connected to the magnets by means of lead wires 70. Similar contact jacks 72, and lead wires 74 are provided on a depending collar member 76 for the reset electromagnet 40.

A card holder 78 may be mounted on the front end of the frame 16 by means of a bracket 80 to hold a card indicating the number of the annunciator drop or other suitable designation.

An example of the manner in which the annunciator may be used is indicated in Fig. 5. In this case the electromagnets 10 of annunciator drops 82, 83, and 84 are connected through respective lead wires 86, 87, and 88 and respective switches or push buttons, not shown, and a main 89, to one terminal of a source of electric energy 90. The current supplied to the electromagnets 10 is returned to a common main or bus bar 91 and from this wire through a lead wire 92, buzzer 93, and lead wire 94, to a main or bus bar 95 connected to the opposite terminal 130

of the source of electric energy 90 by means of a conductor 96. To ensure a steady current for the electrogmagnets a shunt 97 of suitable resistance is placed about the buzz-
5 zei 93 between the wires 92 and 94.

One end of the reset electromagnets 40 is connected to the bus bar 95 and the other terminal to the opposite terminal or pole 10 of the source of electric energy 90 through lead wires 98 to a main or bus bar 99 and thence through a conductor 100 and reset key or switch 101.

As the frame 16 is made of soft iron, it changes or reverses its magnetism very rapidly 15 with alternations in current in the electromagnets and there is a substantially steady field in the air gap 22. The armature 24 is drawn into this magnetic field with equal force regardless of the polarity 20 of the field and therefore independently of the type of current used in the electromagnet coils. As the entire flux of the electromagnets is concentrated in this air gap 22, a very effective and efficient utilization of 25 the current is obtained and a very small current may be successfully employed.

As there are no moving parts other than the armature and parts moving with it, there is no noise or buzzing sounds when 30 the target is reset electrically, nor is there any movement of the mechanism when current is sent through the electromagnet 10 when the drop is in announcing position.

As changes of construction could be made 35 within the scope of my invention, it is desired that all matter contained in the above description or shown in the accompanying drawings shall be interpreted as illustrative and not in a limiting sense.

Having described the invention, what I 40 claim and desire to secure by Letters Patent is:

1. A device of the type described which 45 comprises, a frame of magnetic material, an electromagnet and core mounted on said frame, said frame forming an undivided magnetic circuit for the flux of said electromagnet and forming an air gap with one end of said core through which substantially 50 the entire flux of said electromagnet flows, a pivoted armature having a portion adapted to swing into and out of said gap and a target mounted on said armature.

2. A device of the type described which 55 comprises, a frame of magnetic material, an electromagnet and core mounted in said frame, said frame forming an undivided magnetic circuit for the flux of said electro-

magnet and forming an air gap with one end of said core through which substantially 60 the entire flux of said electromagnet flows, a pivoted armature having tail pieces adapted to extend into said air gap and a target mounted on said armature.

3. A device of the type described which 65 comprises, a frame of magnetic material, an electromagnet and core mounted in said frame, said frame forming a magnetic circuit for the undivided flux of said electromagnet from one end of said core to within 70 a short space of the opposite end of said core and forming an air gap therewith, a pivoted armature adapted to tilt into said air gap, and a target mounted on said armature, the center of gravity of said armature 75 and target being above the pivotal support of said armature.

4. A device of the type described which 80 comprises, a frame of magnetic material, an electromagnet and core mounted in said frame, said frame forming a magnetic circuit for the undivided flux of said electromagnet from one end of said core to within 85 a short space of the opposite end of said core and forming an air gap therewith, a pivoted armature adapted to tilt into said air gap, a target mounted on said armature, the center of gravity of said armature and target being above the pivotal support of 90 said armature, and means for tilting said armature out of said air gap.

5. A device of the type described which 95 comprises, an electromagnet having a core, a magnetic circuit from one end of said core to a plate spaced from the opposite end of 100 the core to form an air gap in the magnetic circuit therebetween through which the undivided flux of said core passes, an armature pivoted to swing into said gap, a target on said armature, and means for tilting said 100 armature out of said gap.

6. A device of the type described which 105 comprises an electro-magnet, a core for said electro-magnet, a frame to which one end of said core is secured, said frame extending about said electro-magnet to overlap the opposite end of said electro-magnet and slightly spaced from said end to form a complete magnetic circuit with said core, and having a short air gap in said circuit between the end of said core and said frame, and a tiltable armature having a portion adapted to enter said air gap, and an indicator target on said armature.

In testimony whereof, I affix my signature.
LEWIS SCRIVEN.
